UNITED STATES PATENT OFFICE.

MILTON E. CHANDLER, OF CHICAGO, ILLINOIS, ASSIGNOR TO STROMBERG MOTOR DEVICES CO., OF CHICAGO, ILLINOIS, A CORPORATION OF ILLINOIS.

FUEL CONTROL.

Application filed November 17, 1924. Serial No. 750,509.

My invention relates to internal combustion engines, and more specifically to an advantageous correlation of the different means for control of fuel supply.

Practically all internal combustion engines are provided with a choke valve or its equivalents, for largely increasing the richness of the mixture to facilitate starting and running while the engine is cold. Many of them are also provided with means for heating all or part of the mixture after it has been formed by the carburetor, and with means for varying the heating action. In an engine equipped both with a hot spot and means for shutting it on and off, and with a choke valve, the hot spot should always be turned down whenever the choke valve is employed, and vice versa, the choke valve should always be wide open before any of the heating action used with the hot spot is eliminated.

Among the objects of the invention may be enumerated a convenient correlation of the controls for actuating the choke valve and the hot spot valve, and positive prevention of improper manipulation of these valves by unskilled operators.

Further objects and advantages of the invention, and various novel details of construction associated primarily with convenience and economy in manufacture, will become apparent as to description per se.

In the accompanying drawings—

Fig. 1 is a plan view of the intake and exhaust manifolds of an internal combustion engine, including the carburetor and controls according to the invention;

Fig. 2 is a side elevation of the same parts;

Fig. 3 is an end view of the same parts;

Fig. 4 is a detail section on line 4-4 of Fig. 1;

Fig. 5 is a face view of the control handle and dial on the base;

Fig. 6 is a side elevation of a modified transmission;

Fig. 7 is an end elevation of the same parts; and

Fig. 8 is an enlarged face view of the Geneva gears.

In the embodiment of the invention selected for illustration, the engine may be provided with a carburetor and inlet and exhaust manifolds of the usual or any preferred construction. In the drawings, the exhaust manifold 10 is offset at 12 over the

inlet manifold 14, the offset portion having a square cross section, and overlying the T of the inlet manifold. Housing 16 may or not be formed integral with the inlet manifold. I have illustrated the integral construction. A butterfly valve 18 is positioned in the middle of offset 12 directly over housing 16. In the position shown in Fig. 2, all the exhaust gases from the cylinders to the right of valve 18 have to pass down out of offset 12 into casing 16, around the T of the inlet manifold and up again on the other side of valve 18. This provides a very strong heat application at the point where it is most efficient. When valve 18 is rotated through 90 degrees from the position shown in Figure 2, it will lie in contact with lip 20 and shoulder 22, completely closing the opening in the exhaust manifold, and effectively isolating casing 16 and the inlet manifold from the hot exhaust gases.

To increase the effectiveness of the control afforded by valve 18, I provide an unusually thick insulating gasket at 24 between casing 16 and the exhaust manifold, to minimize transfer of heat by conduction through the metal.

The carburetor 26 may also be of any suitable or preferred construction provided with the usual choke valve 28.

Both valves 18 and 28 are spring held in the positions shown in Figure 2, valve 18 having a spring 30, see Fig. 1, attached to a suitable arm and resiliently pressing it against a stop lug 32, see Fig. 2; and valve 28 being similarly held in wide open position by a spring 34 acting on a suitable arm and tending to rotate control arm 36 against a suitable stop 38.

Loose on the pintle 40 of valve 18 is a beveled gear 42 having a segmental slot at 44, see Fig. 4, within which pin 46 fixed in shaft 40 may play; an overhanging ear 48 integral with or carried by member 42, engaging the side of a transmission arm 50 also loose on shaft 40. Link 52 connects arms 50 and 36 to actuate the choke valve. It will be apparent that rotation of bevel 42 clockwise, as seen in Fig. 4, will act on pin 46 to rotate pintle 40 and turn off the hot spot valve. Similarly rotation in the opposite direction will act through ear 48, arm 50, link 52 and arm 36 to close the choke valve up to a limit of movement used through contacts between the remote pro-

jecting end 54 of arm 36 and the other side of lug 38.

I have illustrated a suitable transmission for moving bevel 42 in either direction, comprising a rod 56 journaled at 58 in a suitable supporting bracket, and carrying a bevel 60 meshing with bevel 42. The other end of rod 56 passes through the dash 62 and carries an operating handle 64 provided 10 with a pointer 66.

For the convenience of the operator, I may provide suitable indicia on the face plate 68, such indicia in the illustrated embodiment comprising the word "cold" at the center of the range of movement of pointer 66, where the choke is wide open and the hot spot also. Counterclockwise movement of handle 64 will gradually increase the richness of the mixture by closing the choke 15 valve, and clockwise movement of the same lever will decrease the heating action of the hot-spot as the engine heats up. It may be desirable to calibrate the right hand side of the dial in terms of the temperature of the 20 outside air, for the guidance of inexperienced persons in using the proper amount of heating for the conditions under which the car is operating.

As stated above, the conditions of proper 25 engine operation are that the choke valve should never be used unless the hot spot is turned on full, and conversely, the choke should be left wide open whenever the hot spot is turned off. It will be seen that the 30 operator can do anything he pleases with either of the choke valve or the hot spot, but that it is impossible not to leave the other control means in proper condition 35 while such adjustment is made.

In Figures 6, 7 and 8, I have illustrated a 40 mechanical transmission which eliminates the use of springs. Bevel 42 as before transmits rotation from handle 64 to the central pinion 72 of a double Geneva gear comprising 45 duplicate gears 74 and 76 arranged in opposite senses. Gear 74 is on the pindle 40 for valve 18, and gear 76 is on a stub shaft 78 carrying an arm 80 to which link 52 may be connected.

Pinion 72 has teeth at 82 for a small portion 50 of its periphery only, the remainder of the pinion being smooth and of large enough diameter to seat in the cut in sockets 84 on the gears. Each gear is provided with cut 55 in sockets spaced apart 90 degrees with teeth 86 between the same. It will be seen that neither springs nor stops are necessary for either valve 18 or valve 28, and that during the range of movement for valve 18,

valve 28 is always held in proper position 60 by the smooth portion of pinion 72 engaging in the proper socket.

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are 70 intended to be defined and secured to me by the following claims.

I claim:

1. In a control system for internal combustion engines, in combination, a hot spot, 75 a controlling valve for the same, a choke valve, and interconnection between said valves operable to move the hot spot valve to connect the hot spot for service before moving the choke valve to closed position 80 and for moving the choke valve to open position before moving the hot spot controlling valve to disconnect the hot spot.

2. In a control system for internal combustion engines, in combination, a hot spot, 85 a valve for the same, a choke valve, a mechanical control element movable in one direction to close the hot spot valve and in the other direction to close the choke valve, and means for reopening either valve before the 90 other is closed.

3. In a control system for internal combustion engines, in combination, a hot spot, 95 a valve for the same, a choke valve, a mechanical control element movable in one direction to close the hot spot valve and in the other direction to close the choke valve, and means for automatically reopening either valve before the beginning of closure movement of the other valve. 100

4. In a control system for internal combustion engines, the combination of a hot spot, a valve therefor, a choke valve, a control element, a connection between said control element and said hot spot valve adapted 105 to positively close said valve when said control element is moved in one direction, a connection between said choke valve and said control element adapted to positively close said choke valve when said control element 110 is moved in the opposite direction, and means for each valve for causing re-opening movement thereof prior to the positive closure movement of the other valve.

In witness whereof, I hereunto subscribe 115 by name this 13 day of November, 1924.

MILTON E. CHANDLER.
